UNITED STATES PATENT OFFICE.

JOHN F. O'CONNOR, OF CHICAGO, ILLINOIS, ASSIGNOR TO W. H. MINER COMPANY, OF CHICAGO, ILLINOIS, A CORPORATION OF ILLINOIS.

CAR.

SPECIFICATION forming part of Letters Patent No. 789,294, dated May 9, 1905.

Application filed February 17, 1905. Serial No. 246,023.

To all whom it may concern:

Be it known that I, JOHN F. O'CONNOR, a citizen of the United States, residing in Chicago, in the county of Cook and State of Illinois, have invented a new and useful Improvement in Cars, of which the following is a specification.

My invention relates to improvements in railway-cars or other vehicles, and more particularly to the connection between car-body and truck.

Heretofore in the construction of cars the body-bolster has been supported directly on the truck-bolster by center plates and center bolt, or other swivel connection. In this old construction the friction between the center plates is very great when the train of cars passes around sharp curves, so much so that frequently the pressure of the car-wheel flanges against the track-rails to overcome the center-plate friction is four thousand pounds or more, and after the train again passes onto a straight track the car-wheel flanges will frequently continue to hug one rail of the track until knocked or pushed around by a reverse curve of the track, thus occasioning great wear.

The object of my invention is to provide a car-body and truck-bolster connection of a simple, efficient, strong, and durable construction, by means of which the customary center plates may be done away with, as well as the friction incident thereto, and whereby after the truck has been thrown or pushed to one side in passing around a curve and the flanges of its wheels thus caused to hug the rail the truck will be automatically swung back or restored to central position after the curve is passed, so that the flanges of the wheels will thus no longer tend to hug one rail.

My invention consists in the means I employ to practically accomplish this object or result—that is to say, it consists, primarily, in connection with the car body and truck and the body-bolster and truck-bolster of a torsion-rod of suitable diameter to support the load, connected at one end, preferably its

upper end, to the truck-bolster or parts rigidly connected therewith, and at its other end, preferably its lower end, to the body-bolster or an extension or part rigidly connected therewith, so that when the two bolsters swivel or turn in respect to each other as the car passes around a curve the resistance to the turning of the bolster will be a tensional one of the upright car-body supporting or suspending rod instead of a frictional resistance of the center plates, as heretofore, and so that the torsional spring of this rod will itself swing back the truck or restore it to its central position after the car has passed the curved track. I prefer to connect the upper end of the torsion-rod to the truck-bolster, and its lower end to the body-bolster instead of the reverse, as in this way the load is supported by a pulling strain or tension of the rod instead of by a compression strain on the rod in the direction of its length, as would be the case where my invention is practiced by connecting the lower end of the rod to the truck-bolster and its upper end to the body-bolster.

My invention also consists in the construction of parts and devices and in the novel combinations of parts and devices herein shown or described.

In the accompanying drawings, forming a part of this specification, Figure 1 is a rear elevation of a device embodying my invention. Fig. 2 is a central vertical section on line 2 2 of Fig. 1, and Fig. 3 is a horizontal section on line 3 3 of Figs. 1 and 2.

In the drawings, A represents a portion of a car-body, and A' the center sills thereof.

B is the body-bolster, and D the truck-bolster, the same being of any suitable form and construction known to those skilled in the art. The body-bolster B preferably comprises an upper flat bar or member b and a lower channel bar or member b' and a pillar-piece or strut-block b², securely riveted to the upper and lower members b b' and having a central opening b³, through which my car-body and truck-connecting torsion-rod F passes. The truck-bolster D preferably

- comprises a pair of channel-bars d d and a collar d' , securely riveted to the upper flanges of said channels and having a central opening d^2 , through which the body-bolster extension or sleeve B' passes. The body-bolster extension or sleeve B' is rigidly secured by rivets b^4 to the body-bolster and, in effect, constitutes part of the body-bolster, as it is rigidly connected therewith. The body-bolster extension or sleeve B' has near its upper end an enlargement or hub b^5 to give an extended bearing against the truck-bolster collar d' to take the lateral and longitudinal thrust or pressure between car body and truck in the movement of the car. This body-bolster extension or sleeve B' preferably projects or extends downwardly from the lower face of the body-bolster. The truck-bolster D has rigidly secured thereto an extension D' , the same preferably consisting of a pair of channel-bars d^2 , rigidly secured by rivets d^3 to the front and rear faces of the truck-bolster, and a connecting-saddle d^4 , extending between and securely riveted to said bars d^2 at their upper ends by rivets d^5 . The truck-bolster extension D' projects upwardly between the center sills $A'A'$ of the car-body, a free space xx being left between the same and the sills to permit the necessary free swiveling movement of the car-truck in respect to the car-body. The saddle d^4 of the truck-bolster extension D' is provided with a central opening d^6 to receive the upper end of my torsion-rod F , which connects the body and truck bolsters and suspends or supports the car-body on the car-truck. This saddle d^4 is also provided with a slot d^7 to receive the key f in the upper end of the torsion-rod F and which thus connects the upper end of the torsion-rod to the truck-bolster, so that this end of the torsion-rod cannot turn in respect to the truck-bolster. The lower end of the torsion-rod F is provided with a corresponding slot f^2 , through which passes the key f^3 , which extends through the slot d^8 in the lower end of the body-bolster extension or sleeve D' , and thus connects the lower end of the torsion-rod F to the body-bolster, so that this lower end of the torsion-rod cannot turn in respect to the body-bolster. The car-body is thus by my invention suspended or supported by the tension-rod F from the truck, and in the preferred construction of my invention shown in the drawings the tension-rod F supports the car-body from the truck by a tension or pulling strain on said rod F , as the upper end of the rod is connected to the truck-bolster and the lower end of the rod is connected to the body-bolster. In operation when the car passes onto a curved track and the bolsters B and D turn or swivel in respect to each other the turning or swiveling movement of the bolsters is resisted by the torsion of the supporting-rod F , which torsion, however, is much less than

the frictional resistance of the center plates, and the torsion of the tension-rod F will automatically swing back or restore the truck to its central position in respect to the car-body, thus relieving the flanges of the wheels from further abnormal friction against the rail. 70

I claim—

1. In a railway-car the combination of the body-bolster and truck-bolster, with a torsion-rod connected at one end to the truck-bolster and at the other end to the body-bolster and supporting the body-bolster from the truck-bolster, so that when the two bolsters swing or turn in respect to each other 75 when the car passes onto a curved track, said rod will be under torsion and cause the truck to be swung back or restored to its normal or central position when the car passes the curved track, substantially as specified. 80

2. The combination with a body-bolster and a truck-bolster, of a torsion-supporting rod connected at one end to the body-bolster and at its other end to the truck-bolster, substantially as specified. 85

3. The combination with a body-bolster and a truck-bolster, of a torsion-rod connected at its upper end to the truck-bolster and at its lower end to the body-bolster so that said torsion-rod will support the body-bolster from the truck-bolster by a tensile or pulling strain on said rod, substantially as specified. 90

4. The combination with a body-bolster having a downwardly-extending extension or sleeve rigidly connected thereto, of a truck-bolster having an upwardly-projecting extension rigidly connected thereto, and a torsion-rod connected at its upper end to said truck-bolster extension, and connected at its lower end to said body-bolster extension or sleeve, substantially as specified. 100

5. The combination with a body-bolster having a downwardly-extending extension or sleeve rigidly connected thereto, of a truck-bolster having an upwardly-projecting extension rigidly connected thereto, and a torsion-rod connected at its upper end to said truck-bolster extension, and connected at its lower end to said body-bolster extension or sleeve, said torsion-rod being connected to said bolster extensions by keys or pins extending through the ends of said torsion-rod and said extensions respectively, substantially as specified. 110

6. The combination with a body-bolster having a downwardly-extending extension or sleeve rigidly connected thereto, of a truck-bolster having an upwardly-projecting extension rigidly connected thereto, and a torsion-rod connected at its upper end to said truck-bolster extension, and connected at its lower end to said body-bolster extension or sleeve, said truck-bolster having a collar secured thereto furnished with a hole or open- 120

ing through which said body-bolster extension or sleeve extends, substantially as specified.

7. The combination with a body-bolster having a downwardly-extending extension or sleeve rigidly connected thereto, of a truck-bolster having an upwardly-projecting extension rigidly connected thereto, a torsion-rod connected at its upper end to said truck-bolster extension, and connected at its lower end to said body-bolster extension or sleeve, said truck-bolster having a collar secured thereto furnished with a hole or opening through which said body-bolster extension or sleeve extends, and said body-bolster extension or sleeve having an enlargement or hub to give an extended bearing against said collar on said truck-bolster to take the lateral and longitudinal thrust and pressure of the body and truck bolsters in respect to each other, substantially as specified.

8. The combination with a truck-bolster, of a body-bolster and a torsion-rod suspending the body-bolster from the truck-bolster, and torsionally connecting said bolsters, substantially as specified.

9. The combination with a truck-bolster,

of a body-bolster and a torsion-rod suspending the body-bolster from the truck-bolster, and torsionally connecting said bolsters, said truck-bolster having an upwardly-projecting extension to which the upper end of said torsion-rod is connected, and said body-bolster having a downwardly-projecting extension to which the lower end of said torsion-rod is connected, substantially as specified.

10. The combination with a truck-bolster, of a body-bolster and a torsion-rod suspending the body-bolster from the truck-bolster, and torsionally connecting said bolsters, said truck-bolster having an upwardly-projecting extension to which the upper end of said torsion-rod is connected, and said body-bolster having a downwardly-projecting extension to which the lower end of said torsion-rod is connected, and said truck-bolster having a collar secured thereto and surrounding the said body-bolster extension, substantially as specified.
